US0D1049241S

(12) United States Design Patent (10) Patent No.: US D1,049,241 S
(45) Date of Patent: * Oct. 29, 2024

(54) GAMING MACHINE

- (71) Applicant: Aristocrat Technologies, Inc., Las Vegas, NV (US)
- (72) Inventors: Bruce Urban, Las Vegas, NV (US); Ariel Turgel, San Francisco, CA (US); Wei Gu, Daly City, CA (US); Daniel Harden, Palo Alto, CA (US)
- (73) Assignee: Aristocrat Technologies, Inc., Las Vegas, NV (US)
- () Term: 15 Years
- (21) Appl. No.: 29/915,574
- (22) Filed: Nov. 1, 2023

Related U.S. Application Data

- (63) Continuation of application No. 29/869,845, filed on Jan. 10, 2023, now Pat. No. Des. 1,010,741, which is (Continued)

CLAIM

The ornamental design for a gaming machine, as shown and described.

DESCRIPTION

FIG. 1 is a front perspective view of a gaming machine showing our new design;

FIG. 2 is a front view of the gaming machine shown in FIG. 1;

FIG. 3 is a back view of the gaming machine shown in FIG. 1;

FIG. 4 is a right side view of the gaming machine shown in FIG. 1;

FIG. 5 is a left side view of the gaming machine shown in FIG. 1; and,

FIG. 6 is a top view of the gaming machine shown in FIG. 1.

In these drawings, the solid lines illustrate the claimed ornamental design, whereas the broken lines illustrate unclaimed environmental features and form no part of the claimed design.

1 Claim, 6 Drawing Sheets

Related U.S. Application Data

a continuation of application No. 29/750,196, filed on Sep. 11, 2020, now Pat. No. Des. 978,249.
